JOSEPH M. MERROW, OF HARTFORD, CONNECTICUT, ASSIGNOR TO THE MERROW MACHINE COMPANY, OF HARTFORD, CONNECTICUT, A CORPORATION OF CONNECTICUT.

NEEDLE-CLAMP.

1,160,308.

Specification of Letters Patent. Patented Nov. 16, 1915.

Application filed May 28, 1913. Serial No. 770,508.

To all whom it may concern:

Be it known that I, JOSEPH M. MERROW, a citizen of the United States, residing at Hartford, in the county of Hartford, State 5 of Connecticut, have invented certain new and useful Improvements in Needle-Clamps; and I do declare the following to be a full, clear, and exact description of the same, reference being had to the accompanying 10 drawings, forming a part of this specification, and to the figures and letters of reference thereon.

This invention relates to an improved needle clamp wherein means are provided 15 for accurately positioning and securely holding needles.

Objects of the present invention are to provide a needle clamp of simple design and substantial construction which will accurately 20 center and clamp the needle securely in place; to improve the form and arrangement of the centering and clamping means, to simplify the form of the parts whereby the manufacture of the same is facilitated 25 and to provide bearing faces for coöperation with the needle which grip the needle at widely separated points and which will not be liable to become worn or damaged by long continued use.

30 The invention consists in certain novel details of construction and combinations of parts as hereinafter more fully described and particularly pointed out in the appended claims.

35 To more clearly illustrate the invention, I have shown and described but a single embodiment thereof applied to a needle carrier of the type used on the well known Merrow overseaming machines, the said embodiment 40 being particularly adapted for holding and centering curved needles with straight shanks.

In the drawings: Figure 1 is an elevation of the needle carrier of a Merrow overseaming 45 machine, showing a needle and clamping mechanism embodying the present invention. Fig. 2 is an elevation of the structure shown in Fig. 1 from a point of view at the left of Fig. 1. Fig. 3 is an enlarged view, 50 in the same elevation as the Fig. 1, of a portion of the needle carrier alone, showing details in the construction of this portion of the carrier that form a part of my invention. Fig. 4 is an elevation looking at the 55 left hand side of the part shown in Fig. 3.

Fig. 5 is a plan view of the part shown in Figs. 3 and 4. Fig. 6 is an elevation corresponding to Fig. 2 but on an enlarged scale, of the clamp plate alone. Fig. 7 is an elevation looking at the left hand side of the 60 plate shown in Fig. 6. Fig. 8 is an enlarged view of a portion of parts shown in Fig. 2 with the stop pin omitted to more clearly show the manner in which the needle is held. Fig. 9 is an elevation looking at the opposite 65 side of the needle from that in the Fig. 1 to display the slabbed shank. Fig. 10 is a cross sectional view of the needle shank on the line 10—10 of Fig. 9.

Throughout the drawings like characters 70 of reference indicate like parts.

Referring to the embodiment illustrated in the drawings: the letter C indicates the needle carrier adapted to be fulcrumed at T and actuated through the pin L, and the upper portion or "head" c' of which (see Figs. 3, 4 and 5) is constructed to embody certain elements of my improved needle clamp. The said head c' of the carrier C is provided with an integral seat for the needle shank 80 formed by two surfaces c² and c³ c³, preferably plane surfaces intersecting one another at right angles and forming a right angled dihedron. The locations of the said surfaces are determined by the position in 85 which it is desired to secure the needle, since it is against these surfaces that the needle shank is clamped, as hereinafter more fully explained. A bore c⁴ through the head c' is provided for the passage of the stud B and 90 in order that the needle shank may pass through a hole b' in the stud and yet bear against the surface c³, c³, the bore c⁴ is cut down into the surface c³ c³, thus dividing the otherwise plane surface into the two 95 sections as seen in Fig. 3. The bore c⁴ is counterbored at c⁸ where it enters the head c' to receive the head b² of the stud B. To insure the alinement of the hole b' in the stud B with the surface c³ c³, as well as to 100 prevent the stud from turning when its nut is tightened, a pin d is provided as shown in dotted lines in Figs. 4 and 8 to form a key.

A surface or clamp seat c⁵ is formed on the side of the projection or shelf portion 105 (indicated by c⁶ which reference character denotes a face of the said projection or shelf portion) opposite to the surface c³—c³ thereon. This surface c⁵ coöperates with a surface of the clamp plate P as hereinafter ex- 110

plained and should be inclined in a plane parallel to a plane dividing the dihedral angle formed by the surfaces c^2 , c^3-c^3 of the needle shank seat as is shown in the drawings.

The clamp plate P is provided with a recess p^4 having the diverging side walls p' and p^3 , and is provided with the opening p^2 for the passage of the stud B, which opening may be of any suitable form. When the clamp plate P is placed in position as best shown in Figs. 2 and 8, the surface p^3 is adapted to coincide with and to engage the clamp seat c^5 and, the surface p' , in order that it may clamp the needle against both surfaces of the needle shank seat, should, as shown, lie in some plane normal to a plane that divides the dihedral angle formed by the needle shank seat, and thus be inclined and opposed to both of the needle seat surfaces.

When the needle clamp is assembled, as shown in Figs. 2 and 8, the stud B which fits in and projects from the head c' as shown, passes, with suitable clearance, through the opening p^2 in the clamp plate P and receives the nut A. The clamp is then ready to receive the needle. The shank of the needle to be clamped is inserted, as shown, between the needle seating surfaces c^2 , c^3-c^3 and the clamping surface p' , with the slabbed face n^2 of the needle shank n' presented to the surface c^2 . In this position, the needle shank is slipped into the clamp and through the hole b' in the stud B until the end n^3 of the said shank abuts the stop pin s as shown in Figs. 1 and 2. The engagement of the slabbed face n^2 of the needle shank with the seating surface c^2 insures the proper rotative positioning of the needle about the axis of the needle shank n' and also locates the needle in the plane of the face c^2 . When the nut A is tightened, the clamp plate P is drawn bodily toward the head c' and the surfaces p' , p^3 settle on the clamp seat c^5 and the periphery of the needle shank as shown in Figs. 2 and 8 with a sliding action; the surface p' acting as a clamping surface whereby the needle shank is forced against and into contact with the seating surface c^2 due to the direct action of the bolt and nut and, at the same time the said clamping surface p' exerts a wedging action that forces a portion of the adjacent periphery of the needle shank into contact with the surface c^3-c^3 . The cooperating surfaces p^3 and c^5 act as a "sliding fulcrum" during the clamping of the needle: by holding the clamp plate against being moved by the wedging action of the surface p' , by drawing or tending to draw the clamp plate laterally in a manner to supplement the wedging action of the surface p' , and, by supporting the clamp seat end of the clamp plate so as to

distribute the pressure of the stud and nut between the needle shank and the clamp seat as is best shown in Fig. 8 of the drawings.

The contact of the needle shank with said surfaces and the pressure between them simultaneously centers and clamps the needle. Sufficient clearance is allowed between the bottom of the recess p^4 and the face c^6 to insure the clamping of the needle shank and to permit a variation in the size thereof. It will be noted that there are two oppositely inclined surfaces p' and p^3 ; and that the needle is held by three plane surfaces and not in semi-circular grooves wherein it is liable to stick, and therefore, with suitable clearance provided between the stud B and the bore p^2 , the clamp is quite sensitive to the pressure of the nut, so that the needle is free as soon as the pressure of the nut is released. The head c' and the plate P are preferably beveled at c^7 and p^5 for the purpose of deflecting the needle thread toward the center line of the needle and prevent its becoming entangled with or abraded by the clamp.

While I have confined my description to the embodiment illustrated in the drawings, I do not limit myself to the specific carrier described nor to the exact details of construction shown.

Having thus described my invention what I claim as new and desire to secure by Letters Patent of the United States is,—

1. A needle clamp embodying the combination of: a carrying member having a projection thereon, a pair of needle shank seating surfaces lying in intersecting planes and formed on the carrying member and on the carrier projection respectively, a clamp seating surface formed on the side of the projection opposite to the needle shank seating surface thereon, a clamping member having a recess provided with diverging side walls, one of said side walls being adapted to engage the clamp seating surface with a sliding cooperative action and the other of said side walls being adapted to clamp the needle shank against the pair of needle shank seating surfaces of the carrying member, and means for drawing the clamp plate to the carrier, all substantially as shown and described.

2. In a needle clamp for shanked needles and in combination with carrying means, a clamp head having a pair of diverging needle clamping surfaces and an inclined surface, the said inclined surface being parallel with a plane dividing the angle included between the said needle clamping surfaces, a clamp plate having a needle engaging surface and a surface for engaging the inclined surface of the clamp head, means arranged to exert a pressure in a direction inclined to the plane of the inclined surface of the

clamp head, whereby the clamp plate may be caused to exert a wedging action on the needle shank to force the same against the needle engaging surfaces of the clamp head substantially as and for the purposes herein set forth.

3. A needle clamp embodying the combination of a clamp head having a shelf portion thereon, a needle shank seat comprising a pair of diverging surfaces arranged one on the clamp head and one on the shelf portion, the said surfaces being adapted to engage the needle shank at widely separated points of its perimeter, a clamp plate adapted to present a clamping surface to the perimeter of the needle shank, a clamp seat inclined in the direction of a plane dividing the angle included between the surfaces of the needle shank seat, a surface on the clamp plate for engaging the clamp seat, means for forcing the clamp plate surfaces against the needle shank and the clamp seat respectively in a direction inclined obliquely with respect to the surface of the clamp seat whereby the needle shank is forced against one of the surfaces of the shank seat by the direct pressure of the clamp forcing means and is forced against the companion face of the shank seat by the wedging action of the clamp seat.

4. In combination in a needle clamp for slabbed shank needles, a clamp head provided with a pair of substantially integral diverging needle shank seating surfaces one of which is adapted to engage the slabbed portion of the needle shank, and a clamp seat inclined in the direction of a plane dividing the angle between the needle shank seating surfaces, a clamp plate having a pair of diverging surfaces adapted to straddle the clamp seat and the shank of the needle to be clamped, and clamping means for forcing the clamp plate against the clamp seat and the needle shank whereby the clamp seat and the inclined surfaces of the clamp plate force the needle against the needle shank seating surfaces both in the direction of and in a direction transverse to the direction of the pressure of the said clamping

means, thereby simultaneously clamping and centering the needle.

5. In a needle clamp for slabbed shank needles, a clamp head having a pair of diverging surfaces c^2 and c^3 forming a seat for engaging the slabbed face of the needle shank and the periphery thereof, a stop s against which the end of the needle shank is abutted, a clamp plate P having a surface p' disposed in a plane normal to a plane dividing the angle included between the surfaces c^2 and c^3 , means for laterally constraining the clamp plate P , a stud B having its axis extending in a direction inclined obliquely with respect to the surface p' and a nut for the said stud, whereby the surface p' is forced against the needle shank to clamp the slabbed face of the needle shank and force a portion of the periphery thereof against the diverging surfaces of the said needle shank seat with a combined clamping and wedging action, substantially as described.

6. In a needle clamp for slabbed shank needles, a clamp head having a pair of diverging surfaces c^2 and c^3 forming a seat for the slabbed face and a seat for the periphery of the needle shank, and a clamp seat surface c^5 inclined in a direction parallel to a plane dividing the angle included between the surfaces c^2 and c^3 , a clamp plate P having a needle engaging surface p' and a clamp seat engaging surface p^3 , the said surface p^3 coöperating with the surface c^5 of the clamp seat to provide a sliding fulcrum for the clamp plate, and clamping means adapted to draw the clamp plate toward the clamp head in a direction inclined obliquely to the surface c^5 , whereby the surface p' of the clamp plate is forced against the shank of a needle simultaneously in the direction of the line of pressure of the said clamping means and in a direction transverse thereto, substantially as and for the purposes herein set forth.

JOSEPH M. MERROW.
